CONTROL SYSTEM

Filed Dec. 29, 1924

BY
Joseph G. Schofield
ATTORNEY

UNITED STATES PATENT OFFICE.

ROBERT C. DEALE, OF PLAINFIELD, NEW JERSEY, ASSIGNOR TO NILES-BEMENT-POND COMPANY, OF NEW YORK, N. Y., A CORPORATION OF NEW JERSEY.

CONTROL SYSTEM.

Application filed December 29, 1924. Serial No. 758,680.

My invention relates to control systems and particularly to control systems for operating planers and other machine tools.

One object of my invention is to provide 5 a control system for a machine tool that shall govern a feed motor to effect feeding movements of the cutting tools at different rates of speed in a new and improved manner and that shall operate the feed motor to effect 10 traverse movement of the tools at different rates of speed.

Another object of my invention is to provide 15 a control system for operating a machine tool having a reciprocating member that shall operate a pilot switch at one end of the stroke of the reciprocating member for operating a holding switch and that shall operate the pilot switch in a reverse direction at the opposite end of the stroke of the 20 reciprocating member for effecting operation of the feed motor by means of the holding switch.

A further object of my invention is to provide 25 a planer control system of the above indicated character that shall be provided with new and improved means for traversing the cutting tools at different rates of speed.

In operating machine tools, and particularly in operating planers, it is desirable to 30 control the feeding and the traversing movements of the cutting tools by means of an auxiliary or feed motor which is operated from the same source of power as the main motor. In a control system constructed in 35 accordance with my invention, a main motor, which is controlled by a pilot switch in accordance with the movement of the work carrying table, is provided for reciprocating the table. A feed motor, which is preferably 40 mounted on the cross rail of the planer, is provided, not only for effecting feeding movements of the cutting tool, but also for effecting traverse movements of the cutting tool. During the feeding operation, the feed 45 motor is operated in one direction to effect feeding movements at a predetermined rate and is operated in a reverse direction to effect feeding movements at a different rate. In controlling the feed motor, the pilot switch, 50 at one end of the stroke of the reciprocating member, effects operation of a holding switch which is provided with a holding circuit.

The holding circuit for the switch is normally closed and maintains the holding switch in operative position. At the opposite 55 end of the stroke of the reciprocating member, the pilot switch effects operation of a feed switch through the holding switch. The feed switch effects operation of the feed motor. After a predetermined operation of 60 the feed motor, the holding circuit for the holding switch is opened. A feed reverse switch is provided for reversing the connections of the pilot switch to the holding switch and to the feed switches in order to effect 65 feeding movements at the opposite end of the stroke of the reciprocating member.

In the copending application of Nicholas Marcalus, Serial No. 756,054, filed December 15, 1924, for a planer is disclosed a machine 70 which is adapted to be operated by a control system constructed in accordance with my invention. Moreover, in the application of Nicholas Marcalus, Serial No. 756,054, filed December 15, 1924, is disclosed a switch of 75 the type shown in this application which is preferable for limiting the feeding operation of the feed motor.

In the accompanying drawing:

Figure 1 is a diagrammatic view of a planer 80 adapted to be operated by a control system constructed in accordance with my invention.

Fig. 2 is a diagrammatic view of a control system, constructed in accordance with my 85 invention.

Referring to Fig. 1 of the drawing, a planer is illustrated having a bed 1, a work carrying table 2, and uprights 3. A suitable cross rail 4, which carries a cutting tool 5, is mounted 90 on the uprights 3. A feed motor 6 is preferably mounted on a bracket 7, which projects from the cross rail 4. The feed motor 6 controls the feeding and traversing movements of the cutting tool 5 in the manner described 95 in the application of Nicholas Marcalus, Serial No. 756,054.

A main motor 8, which is controlled by a pilot switch 9, is provided for reciprocating the table 2. The pilot switch 9 is supported 100 on the bed 1 of the machine and is operated in accordance with the movement of the table 2. The table 2 carries two adjustable dogs 10 and 11, which engage levers 12 and 13 for

operating the pilot switch 9. The levers 12 and 13 are connected to the pilot switch by means of links 14. The control of the pilot switch by the planer table is well-known and further description is deemed unnecessary.

Referring to Fig. 2 of the drawing, the main motor 8 is shown comprising an armature 15, a commutator winding 16 and a shunt field-magnet winding 17. The feed motor 6 comprises an armature 18, a shunt field-magnet winding 19 and a series field-magnet winding 20. The main motor 8 is controlled by two main switches 21 and 22, and an accelerating switch 23. The feed motor is controlled by two feed switches 24 and 25 and an accelerating switch 26.

The main switch 21 comprises an operating magnet 30, a holding magnet 31, and a switch arm 27 having two contact members 28 and 29 mounted thereon. The contact member 28 engages a stationary contact member 32 in the operative position of the switch arm and the contact member 29 engages a stationary contact member 33 in the released position of the switch arm. A pin 34 is mounted on the lever 27 for operating a switch 35 to insert a resistor 36 in the circuit shunt field-magnet winding 17 during the return stroke of the planer.

30 The switch 21 is operated to effect a return stroke of the table 2 and the switch 22 is operated to effect a cutting stroke of the planer table. During the cutting stroke, a resistor 37 is included in the circuit of the shunt field-magnet winding 17 whereas during the return stroke the resistors 36 and 37 are included in the circuit of the shunt field-magnet winding. A switch 38 is closed by the switch arm 27 in the operative position of the switch 21 to complete the energizing circuit for the accelerating switch 23.

The main switch 22 comprises an energizing magnet 43, a holding magnet 44, and a switch arm 40 having two contact members 41 and 42 mounted thereon. In the operative position of the switch arm, contact member 41 engages stationary contact member 45 and in the released position of the switch arm contact member 42 engages a stationary contact member 46. In the operative position of the main switch 22, the switch arm 40 engages a resilient contact member 47 for completing a circuit to effect operation of the accelerating switch 23.

55 The accelerating switch 23 comprises an operating magnet 48 and a switch arm 49 having two contact members 50 and 51 mounted thereon. The contact member 51 is insulated from the switch arm 49 and in the released position of the switch arm bridges two stationary contact members 52. The contact member 50 engages a stationary contact member 53 in the operative position of the switch arm 49.

65 The feed switch 24 comprises an energizing

magnet 55, a holding magnet 56, and two switch arms 57 and 58. The switch arm 58 carries a contact member 59 which engages a stationary contact member 60 in the operative position of the switch. The switch arm 57 carries two contact members 61 and 62. In the released position of the switch arm, contact member 62 engages a stationary contact member 63 and in the operative position of the switch arm, contact member 61 engages a stationary contact member 64. An auxiliary switch 65 is operated by the switch arm 58 to prevent the operation of the feed switch 25 when the feed switch 24 is in an operative position.

The feed switch 25 comprises an energizing magnet 66, a holding magnet 67, and two switch arms 68 and 69. The switch arm 69 carries a contact member 70 which engages a stationary contact member 71 in the operative position of the switch. The switch arm 68 carries two contact members 72 and 73. In the released position of the switch, the contact member 73 engages a stationary contact member 74 and in the operative position of the switch, the contact member 72 engages stationary contact member 75. An auxiliary switch 76 is operated by the switch arm 69 to prevent operation of the feed switch 24 when the feed switch 25 is in an operative position.

The accelerating switch 26 comprises an operating magnet 77 and a switch arm 78 having a contact member 79 mounted thereon. The contact member 79 engages a contact member 80 in the operative position of the switch. The coil 77 of the accelerating switch is connected across the armature of the feed motor. The switch serves to short circuit a resistor 81 from the feed motor circuit. A circuit breaker 82, comprising switch arms 83 and 84, is provided for connecting the circuits of the feed and the main motor to supply conductors 85 and 86.

The pilot switch 9 comprises contact segments 87, 88 and 89 which engage contact fingers 90 to 98, inclusive. The pilot switch controls the operation of main switches 21 and 22 and the accelerating switch 23 to govern the operation of the main motor 8 and controls the operation of the feed switches 24 and 25 to govern the operation of the feed motor 6.

A holding switch 100, comprising an operating magnet 101 and a switch arm 102, is provided between the pilot switch 9 and the feed switches 24 and 25. The switch arm 102 carries a contact member 103 which engages a stationary contact member 104 in the operative position of the switch. A holding circuit for the magnets 101 is provided through a resistor 105 and an auxiliary feed switch 106. The holding circuit for the magnet 101 does not permit sufficient current to flow through such magnet to operate the

switch from a released position. The holding circuit only energizes the magnet 101 sufficiently to hold the switch 100 in an operative position after operation thereof. The 5 auxiliary feed switch 106 is disclosed and claimed in the copending application of Nicholas Marcalus, Serial No. 756,054.

A two pole double throw switch 107 is provided for reversing the connections of the 10 pilot switch 9 to the holding switch 100 and the feed switches in order to reverse the end of the planer stroke at which the feeding operation takes place. The switch 107 comprises two switch arms 108 and 109, which 15 engage contact members 110 to 113, inclusive. A switch arm 114, which engages a contact member 115 and a contact member 116, is controlled in accordance with the rate of the feeding movement in the manner disclosed 20 in the copending application of Nicholas Marcalus, Serial No. 756,054. The switch arm 114 selectively operates either the switch 24 or the switch 25 and accordingly determines the direction of rotation of the feed 25 motor 6.

Two push button switches 117 and 118 are provided for effecting traversing operation of feed motor 6 at different rates of speed. In the released position, the switch 117 30 bridges contact members 119 and in the operative position bridges contact members 120. The switch arm 118 in the released position bridges contact members 121 and in the operative position bridges contact members 122.

Assuming the table 2 to be at the end of the cutting stroke, the dog 10 engages the lever 12 for operating the pilot switch 9. The pilot switch 9 is operated to bridge the contact fingers 97 and 98 by the contact segment 35 87. The contact segment 88 bridges the contact fingers 90 and 91 and the contact segment 89 bridges contact fingers 94 and 95. The bridging of the contact fingers 97 and 98 by the contact segment 87 completes a circuit 40 for operating the main switch 21 to reverse the direction of rotation of the main motor 8. The energizing circuit for the main switch 21 extends from the supply conductor 86 45 through the switch arm 84, contact fingers 97 and 98, which are bridged by the contact segment 87, coil 30, switch arm 40, contact members 42 and 46, holding coil 44, and the switch arm 83 to the supply conductor 85.

The main switch 21 completes a circuit 55 through the main motor 8 which extends from the supply conductor 85 through the switch arm 84, contact members 32 and 28, switch arm 27, resistor 130, winding 16, armature 15, switch arm 40, contact members 42 and 60 46, holding magnet 44, and switch arm 83 to the supply conductor 85. Upon operation of the main switch 21, the accelerating switch 23 is operated by a circuit which extends from one terminal of the armature 15 through the 65 coil 16, contact fingers 90 and 91, which are

bridged by the contact segment 88, operating magnet 48, switch 38, and the switch arm 40 to the other terminal of the armature 15. The accelerating switch 23 excludes the resistor 130 from the circuit of the main motor. 70

Prior to the operation of the accelerating switch 23, the shunt field-magnet winding 17 is connected directly across the supply conductors 85 and 86. The circuit through the shunt field-magnet winding extends from the 75 supply conductor 86 through the switch arm 84, contact members 52, which are bridged by the contact segment 51, winding 17, and the switch arm 83 to the supply conductor 85. Upon operation of the accelerating switch 23, the direct connection of the shunt field-magnet winding across the supply conductors is opened and the circuit extends through the resistors 36 and 37. Such circuit of the shunt field-magnet winding extends from the supply conductor 86 through the switch arm 84, resistors 36 and 37, winding 17, and the switch arm 83 to the supply conductor 85. Inasmuch as the resistors 36 and 37 are included in the circuit of the shunt field-magnet 80 winding, it is apparent the return stroke of the planer is effected at increased speed. 90

The bridging of the contact fingers 94 and 95 by the contact segment 89 completes a circuit for operating the holding switch 100. The circuit through the operating magnet of the holding switch extends from the supply conductor 86 through the switch arm 84, contact members 94 and 95, which are bridged by the contact segment 89, switch blade 109, magnet 101, and the switch arm 83 to the supply conductor 85. In the above circuit, it is assumed the switch 107 is in its lower position in order to effect a feeding movement at the end of the return stroke. If the switch 107 is in its upper position, a feeding movement is effected at the end of the cutting stroke. In the present position of the switch 107 no movement whatever is effected by the feed motor until the table 2 reaches the end of the return stroke. 100 105 110

At the end of the return stroke, the dog 11 engages the lever 13 for reversing the position of the pilot switch 9. In the reversed position of the pilot switch, the contact segment 87 disengages the contact members 97 and 98 to release the main switch 21. Upon release of the main switch 21, a dynamic braking circuit is completed through the main motor 8. Such circuit extends through the holding magnets 31 and 44 of the main switches 21 and 22 to prevent operation of such switches until the dynamic braking current ceases to flow. The contact segment 87 is moved to bridge the contact fingers 90 and 91 for operating the accelerating switch 23 upon operation of the main switch 22. 115 120 125

The contact segment 88 bridges contact fingers 92 and 93 for operating the main switch 22. The energizing circuit for the main switch 130

22 extends from the supply conductor 86 through the switch arm 84, contact fingers 92 and 93, which are bridged by the contact segment 88, magnet 43, switch arm 27, contact members 29 and 33, magnet 31, and the switch arm 83 to the supply conductor 85. The main switch 22 is operated and a circuit is completed through the main motor 8 which extends from the supply conductor 86 through the switch arm 84, contact members 45 and 41, switch arm 40, armature 15, compensating winding 16, accelerating resistor 130, switch arm 27, contact members 29 and 33, holding coil 31, and the switch arm 83 to the supply conductor 85. The main motor 8 is operated in a reverse direction for operating the table 2 to effect a cutting stroke.

The accelerating magnet 23 is operated by a circuit which extends from one terminal of the armature 15 through the winding 16, contact members 90 and 91, which are bridged by the contact segment 87, coil 48, contact member 47, and the switch arm 40 to the other terminal of the armature 15.

25 The contact segment 89 is moved out of engagement with the contact finger 94 and into engagement with the contact finger 96. The separating of the contact segment 89 from the contact fingers 94 opens the energizing circuit for the holding switch 100. However, a holding circuit is normally closed through the coil 101 of the switch 100 so that the switch is maintained in an operative position. The holding circuit for the switch 100 extends from the supply conductor 86 through the switch arm 84, switch 106, resistor 105, coil 101, and the switch arm 83 to the supply conductor 85.

40 The bridging of the contact fingers 95 and 96 by the contact segment 89 completes a circuit through the holding switch 100 for operating the feed switch 24. The circuit extends from the supply conductor 86 through the switch arm 84, contact members 95 and 96, which are bridged by the contact 89, switch arm 108, contact members 104 and 103, switch arm 102, switch arm 114, contact member 115, contact members 119, which are bridged by the switch 117, coil 55, switch 76, and the switch arm 83 to the supply conductor 85. The feed switch 24 is operated and a circuit is completed for operating the feed motor 6. The circuit through the feed motor extends from the supply conductor 86 through the switch arm 84, series field-magnet winding 20, accelerating resistor 81, contact members 64 and 61, switch arm 57, armature 18, switch arm 58, contact members 59 and 60, and the switch arm 83 to the supply conductor 85.

45 The feed switch 24 is released to stop the feeding movement by releasing the holding switch 100. The holding switch 100 is released by opening the holding circuit which extends through the switch 106. The switch

106, which serves as a limit, is operated by the feed motor and accordingly is operated at only one end of the stroke. The switch 106, which is included in the holding circuit through the coil 101, is disclosed in the companion application of Nicholas Marcalus, Serial No. 756,054, and comprises a notched disk 131 which engages two contact members 132 and 133. Upon slight rotation of the disk 131, the disk is separated from the contact members 132 and 133. Such momentary opening of the holding circuit permits the release of the switch 100 and the release of the feeding switch to stop the feed motor.

50 The switch arm 114 is maintained in engagement with the contact member 115 through a certain range of feeding movements. When the rate of feeding is raised above a predetermined point, the switch arm 114 is moved into engagement with the contact member 116. The operation of the switch 114 is described in the copending application of Nicholas Marcalus Serial No. 756,054. If the switch arm 114 is in engagement with the contact member 116, the feed switch 25 is operated in place of the feed switch 24 and the feed motor 6 is operated in a reverse direction. The energizing circuit for the feed switch 25 extends from the supply conductor 86, through the switch arm 84, contact members 95 and 96 which are bridged by the contact segment 89, switch arm 108, contact members 103 and 104, switch arm 102, switch arm 114, contact member 116, contact members 121, which are bridged by the switch 118, magnet 66, switch 65, and the switch arm 83 to the supply conductor 85.

55 The circuit completed by the switch 25 through the feed motor extends from the supply conductor 86, through the switch arm 84, series field-magnet winding 20, resistor 81, contact members 75 and 72, switch arm 68, armature 18, switch arm 69, contact members 70 and 71, and switch arm 83 to the supply conductor 85. The coil 77 of the accelerating switch 26 is connected across the armature 18. The switch 26 serves to short circuit the resistor 81. As above set forth the feed motor 6 is operated in one direction to effect feeding movement at one rate and is operated in a reverse direction to effect feeding movements at a different rate. Upon release of either the feed switch 24 or the feed switch 25, a dynamic braking circuit is completed through the feed motor. The dynamic braking circuit extends from one terminal of the armature 18, through the switch arm 69, switch arm 57, contact members 62 and 63, dynamic braking resistor, contact members 73 and 74, switch arm 68 and the switch arm 58 to the other terminal of the armature 18. At the end of the cutting stroke, the above cycle of operations is again repeated.

In case it is desired to effect traverse movement of the feed motor 6, the switch 117 or the switch 118 is operated according to the rate of traversing movement that is desired.

- 5 Upon operation of the switch 117, a circuit is completed for operating the feed switch 25. Such circuit extends from the supply conductor 86 through the switch arm 84, contact members 120, which are bridged by the
 10 switch 117, magnet 66, switch 65, and the switch arm 83 to the supply conductor 85. The feed motor is continuously operated at a predetermined direction and a traversing movement is effected at a predetermined
 15 rate.

In case the traverse switch 118 is operated, the feed switch 24 is energized for reversing the direction of rotation of the feed motor 6 and accordingly for varying the rate of the
 20 traversing movement. Upon operation of the switch 118, a circuit is completed from the supply conductor 86 through the switch arm 84, contact members 122, which are bridged by the switch 118, contact members
 25 119, which are bridged by the switch 117, magnet 55, switch 76, and the contact arm 83 to the supply conductor 85.

In the above system, it will be noted the switch 107 serves to determine the end of the
 30 stroke at which a feeding movement by the motor 6 will be effected. The switch arm 114 determines the direction of rotation of the motor 6 during the feeding movement and accordingly determines the rate of the feeding
 35 movement. The pilot switch 9 at one end of the stroke effects operation of the holding switch and at the opposite end of the stroke operates one of the feed switches through the holding switch 100. The switch 106
 40 which is operated by the feed motor, serves to limit the extent of the feeding movement.

Modifications in the system and in the arrangement and location of parts may be made within the spirit and scope of my invention
 45 and such modifications are intended to be covered by the appended claims.

What I claim is:

1. In a control system, the combination with a reciprocating member, and a motor, of a holding switch, means comprising a pilot switch operated by the reciprocating member for operating the holding switch at one end of the stroke of the reciprocating member, a holding circuit for holding the holding switch in operated position upon operation by said pilot switch, and means comprising a circuit completed by said pilot switch at the opposite end of the stroke of the reciprocating member for effecting operation of the motor through the holding switch.

2. In a control system, the combination with a reciprocating member, and a motor, of an auxiliary switch for operating the motor, a holding switch, means comprising a pilot switch operated by the reciprocating

member for operating the holding switch at one end of the stroke of the reciprocating member, a holding circuit for holding the holding switch in operated position upon operation by said pilot switch, and a circuit completed by said pilot switch at the opposite end of the stroke of the reciprocating member for operating the auxiliary switch through the holding switch.

3. In a control system, the combination with a reciprocating member, and a motor, of auxiliary switches for operating the motor in a forward and in a reverse direction, a holding switch, means comprising a pilot switch operated by the reciprocating member for operating the holding switch at one end of the stroke of the reciprocating member, a holding circuit for holding the holding switch in operated position upon operation by said pilot switch, and a circuit completed by said pilot switch at the opposite end of the stroke of the reciprocating member for operating one of the auxiliary switches through the holding switch.

4. In a control system, the combination with a reciprocating member, and a feed motor, of auxiliary switches for operating the feed motor in a forward and in a reverse direction, a holding switch having a normally closed holding circuit, means comprising a pilot switch operated by the reciprocating member for operating the holding switch at one end of the stroke of the reciprocating member and for operating one of the auxiliary switches through the holding switch at the opposite end of the reciprocating member stroke, and means for opening said holding circuit to release the holding switch and limit the movement of the feed motor after a predetermined operation thereof.

5. In a control system, the combination with a reciprocating member, a motor, and auxiliary switches for operating the motor in a forward and in a reverse direction, of a holding switch having a normally closed holding circuit, means comprising a pilot switch operated by the reciprocating member for operating the holding switch at one end of the stroke of the reciprocating member and for operating one of the auxiliary switches through the holding circuit at the opposite end of the reciprocating member stroke, and a switch for reversing the connections of the auxiliary switches to the holding switch to reverse the direction of rotation of the motor when operated by the pilot switch.

6. In a control system for a machine tool, the combination with a reciprocating member, a feed motor, and feed switches for operating the feed motor in a forward and in a reverse direction, of a holding switch having a normally closed holding circuit, means comprising a pilot switch operated by the reciprocating member for operating the hold-

of the reciprocating member for operating one of the feed switches through the holding switch.

14. In a control system for a machine tool, the combination with a reciprocating member, a main motor for operating the reciprocating member, a feed motor, and a pilot switch operated by the reciprocating member for controlling the main motor, of two feed switches for operating the feed motor in a forward and in a reverse direction, a holding switch, means comprising said pilot switch for operating the holding switch at one end of the stroke of the reciprocating member, a holding circuit for holding the holding switch in operated position upon operation by said pilot switch, a circuit completed by said pilot switch in a reverse position at the other end of the stroke of the reciprocating member for operating one of the feeding switches through the holding switch and a switch for reversing the connections of the feed switches to the holding switch to reverse the direction of rotation of the feed motor when operated by the pilot switch.

15. In a control system for a machine tool, the combination with a reciprocating member, a main motor for operating the reciprocating member, a feed motor, and a pilot switch operated by the reciprocating member for controlling the main motor, of two feed switches for operating the feed motor in a forward and in a reverse direction, a holding switch, means comprising said pilot switch for operating the holding switch at one end of the stroke of the reciprocating member, a holding circuit for holding the holding switch in operated position upon operation by said pilot switch, a circuit completed by said pilot switch in a reverse position at the other end of the stroke of the reciprocating member for operating one of the feed switches through the holding switch, and a switch for reversing the connections of the pilot switch to the holding switch to effect a feeding movement at the opposite end of the stroke of the reciprocating member.

16. In a control system for a machine tool, the combination with a reciprocating member, a main motor for operating the reciprocating member, a feed motor, and a pilot switch operated by the reciprocating member for controlling the main motor, of two feed switches for operating the feed motor in a forward and in a reverse direction, a holding switch, means comprising said pilot switch for operating the holding switch at one end of the stroke of the reciprocating member, a holding circuit for holding the holding switch in operated position upon operation by said pilot switch, a circuit completed by said pilot switch in a reverse position at the other end of the stroke of the reciprocating member for operating one of the feed switches through the holding switch, a switch for re-

versing the connections of the feed switches to the holding switch to reverse the direction of rotation of the feed motor when operated by the pilot switch, and a switch for reversing the connections of the pilot switch to the holding switch to effect a feeding movement at the opposite end of the stroke of the reciprocating member.

17. In a planer control system, the combination comprising a main motor, a table reciprocated by said main motor, a feed motor operated at one end only of the table stroke, means operated by said table for completing a circuit to operate the feed motor, and a limit switch operated by the feed motor at only one end of the table stroke for limiting the movement of the feed motor.

18. In a planer control system, the combination comprising a main motor, a table reciprocated by said main motor, a feed motor, a pilot switch operated by said table at each end of the table stroke for controlling the main motor, a limit switch for limiting the operation of the feed motor, means for operating the limit switch at only one end of the table stroke, and means controlled by the pilot switch for operating the feed motor at one end only of the table stroke to effect feeding movements.

19. In a planer control system, the combination comprising a reciprocating table, a feed motor operated at only one end of the table stroke, a pilot switch operated in accordance with the movement of the table, means operated by the pilot switch at one end of the table stroke for preparing a circuit to operate the feed motor and operated by the pilot switch at the other end of the stroke for completing the circuit to operate the feed motor, and a limit switch operated at only one end of the table stroke for limiting the movement of the feed motor.

20. In a planer control system, the combination comprising a reciprocating work table, a feed motor, means for automatically operating the feed motor at one end only of the table stroke, and a limit switch for limiting the feeding movements of the feed motor and operated at only one end of the table stroke by the feed motor.

21. In a planer control system, the combination comprising a reciprocating table, a feed motor for effecting a feeding movement at only one end of the table stroke, a limit switch for limiting the feeding movement of the feed motor and operated at only one end of the table stroke by the feed motor, a pilot switch operated in accordance with the movement of the table, and means operated by the pilot switch at one end of the table stroke for preparing a circuit to operate the feed motor and operated at the other end of the stroke for completing the circuit to operate the feed motor.

22. In a planer control system, the combi-

nation comprising a reciprocating table, a feed motor, a pilot switch operated in accordance with the movement of the table, a limit switch for limiting the operation of the feed motor, means for operating the limit switch at only one end of the table stroke, means for operating the feed motor by the pilot switch only at one end of the table stroke and means comprising an auxiliary switch for selecting 10 the end of the stroke at which operation of the feed motor and the limit switch is effected.

23. In a planer control system, the combination comprising a reciprocating table, a feed motor, a pilot switch operated in accordance with the movement of the planer table, means operated by the pilot switch at one end of the table stroke for preparing a circuit for operating the feed motor and operated by the pilot switch at the opposite end of the table 20 stroke for completing the feed motor operating circuit, and means comprising a limit switch operated by the feed motor for limiting the operation of the feed motor.

24. In a planer control system, the combi-

nation comprising a reciprocating table, a feed motor operated only at one end of the table stroke, a pilot switch operated at each end of the table stroke, and means operated by the pilot switch at one end of the table stroke for preparing a circuit to operate the feed motor and operated at the opposite end of the table stroke for completing the circuit to operate the feed motor.

25. In a planer control system, the combination comprising a reciprocating table, a feed motor, a limit switch for limiting the operation of the feed motor, means for operating the limit switch at only one end of the table stroke, a pilot switch operated at each end of the movement of the table for operating the feed motor only at one end of the table stroke, and means for selecting the end of the table stroke at which operation of the feed motor and the limit switch takes place.

In testimony whereof, I hereto affix my signature.

ROBERT C. DEALE.
